Robert Burdall, Wilkes County, Georgia

Sellers' Patent.

The sole and only right of the Seller's Patent, and making part of the same, containing a description in the words of the said Robert Burdall, himself of his improvement in the said mill.

To all to whom these presents shall come.

Be it known that I Robert Burdall of Wilkes County & State of Georgia have invented a new & useful improvement in running of millstones, & that the following is a full & exact description of the construction & operation of the said machine as invented or improved by me. A spindle extends from the bridge to the bottom stone one foot above the runner, the spindle is about three inches square near the lower end & four inches in diameter at the shoulder & round from thence down, about six inches above at the shoulder there is another in diameter, two inches at the upper end in diameter. Projected from the neck to the shoulder, the runner is confined to the spindle by two drivers, one inserted in the face of the runner about two inches deep, the other inserted on top a little below the surface; both the drivers are neatly fitted in, that the spindle in passing thro' the eye of the runner may stand perpendicular from the face of the stone, the lower driver has four bars about six inches long & two square projecting from the collar, that being two & half inches deep & three quarters of an inch thick, having one half of the circumference on the lower edge taken out three quarters of an inch deep from the edge, (see a fore-mentioned) a groove mortise in the shoulder of the spindle receives this projection on the driver which prevents the spindle from turning in the driver & projects the runner, the upper driver has four bars six inches long, three inches wide & one & half thick, the other is the same as to one edge on top to fit in with the groove

from breaking out of the spindles if fallen from the beam, the collar is four inches deep & half an inch thick (see upper view) the beams made in this manner are of iron & eight inches thick being least sufficiently large with these bars to answer the purpose, an iron key passes thro' the spindle above the upper collar for urging it down on the beam, lower down at the shoulder of the spindle (see spindle) by this means the beam is well fixed on the spindle, the lower end of the spindle runs in a slot in the bridge tree, the upper end is confined by a beam one foot long, twelve inches wide, 4 inches thick, laid lengthwise, that the centre of the beam, a bar of wood or metal is fastened to the top of the beam on each side of the spindle, six inches long, four inches deep & two thick (see view of the top & top view of the beam) these bars are kept tight on the journal of the spindle by keys passing thro' the beam one inch thick, about two inches from the top of the beam passing thro' a part of the key over the spindle on the beam is a stirrup with a nail to run down in the end of the spindle to prevent the spindle from rising or to add any weight to the beam that may be necessary; two bolts pass thro' the beam with iron & tap to confine the stirrup a mortise in the foot of the stirrup three inches long for the bolts a nail of the stirrup being driven each way lengthwise with the beam (see side and top view of the stirrup) if in raising or lowering the bridge tree the spindle should be thrown from a perpendicular as the beam can be made perpendicular by the key slipping the stirrup to suit the spindle; the screw in the stirrup is pointed with steel shapes intersecting the end of the spindle, the post to support the beam, are made effect by six inch, at the base having two pieces that pass thro' the beam six inches by them another piece two inches long at the base having one turn for a windlass by two & a half, this piece is formed to be fastened to a second piece on one side in the centre edge wise this forms a post with the beam passing thro' the beam key and the nail more to prevent the beam being pulled (see side view and view of the post) the post is not fastened into the back frame plate or top plate of frame but the other end of the post is formed.

For use in the grain mill a convenient办法 of the best form
is to fit a piece of wood in a vice ten inches long with a hole in the
center which is in diameter for the spindle to pass thru. a cap of sheet iron
is made in diameter and about an inch deep with a hole cut in the
center large enough for to fit the spindle below the shoulder. This cap
is made fast to the lower end of the vice by two clamps around the bridge tube
of sheet iron, four inches in diameter & twelve long passes thru the hole
in the bush extending up under the cap as near the bearing as possible
to not touch it. The tube can be kept in place by four wedges, passing
between the bush & the tube, this prevents the grain from passing thru
the bush. A tube of tin may be fitted in the eye of a iron rod running nearly up
to the shoulder to prevent the grain from blowing out. It will be made
of two pieces of sheet iron about five inches in diameter with a hole cut in each
to receive the spindle with four or six rounds of iron six inches long this
fitting tight on the spindle and serve for the saddle staff. The bridge piece is
engaged to run parallel with the beam that the spindle may be kept
perpendicular. This plan may be applied to the mills as well as gear.
